IGNITION SYSTEM

Brooks H. Short, Anderson, and Andrew G. Tynan, Kokomo, Ind., assignors to General Motors Corporation, Detroit, Mich., a corporation of Delaware

Application August 18, 1945, Serial No. 611,402

2 Claims. (Cl. 123—148)

1

This invention relates to an ignition system for an internal combustion engine and more particularly for automotive use.

It is an object of the present invention to provide an ignition system of high frequency such as will provide satisfactory ignition for an engine operating under a relatively high compression even when the spark plugs are fouled. In the disclosed embodiment of the present invention, this object is accomplished by the use of a direct current source for charging a main condenser and an auxiliary condenser and by controlling the discharge of the main condenser through the primary circuit of a high frequency ignition coil by means of a hydrogen filled thyratron which is caused to be conductive by the discharge of the auxiliary condenser, the discharge of which is effected by the closing of the timer contacts.

A further object of the invention is to provide a suitable high frequency ignition coil.

Further objects and advantages of the present invention will be apparent from the following description, reference being had to the accompanying drawing, wherein a preferred embodiment of the present invention is clearly shown.

In the drawings:

Fig. 1 is a wiring diagram illustrating a form of the invention.

Fig. 1A is a chart illustrating the operation.

Fig. 2 is a plan view of the ignition coil together with its housing and terminals, the cover of the housing being removed.

Fig. 3 is a sectional view on line 3—3 of Fig. 2, except that the ignition coil is shown in side elevation.

Fig. 4 is a plan view of one of the ignition coil sections.

Fig. 5 is a plan view of the ignition coil core.

Fig. 6 is a fragmentary, sectional view of one of the ignition coil sections showing the primary and secondary winding layers and layers of insulation.

Referring to Fig. 1, a terminal 10 is connected with a high voltage D. C. source for example, one which will impress a voltage of 2500 volts between terminal 10 and ground *g*. Voltage divider resistances 11 and 12 are connected between terminal 10 and ground. Between the tap 13 and ground, there is a voltage drop of 200 volts. A resistance 14 connects tap 13 with an auxiliary condenser 15 which is charged, for example, at 200 volts. Terminal 10 is connected by resistance 16 with the main condenser 17 connected with primary *P* of an ignition coil 30 whose secondary *S* is connected with an ignition distributor 20 by which connections are made in recurrent sequence with the various spark plugs 21 of the engine.

The discharge of condenser 17 is controlled by a hydrogen filled thyratron 22 having a plate 23

connected with condenser 17, having a grid 24 connected through resistance 25 with a contact 26 of an ignition timer engageable with a timer contact 27 connected with condenser 15. The cathode 28 is connected between ground and terminal 28a on which is impressed a voltage of, for example, six volts for heating the cathode. A resistance 29 is connected between the cathode and the grid in order to prevent the tube 22 becoming conducting except at the proper time.

The operation of the system is as follows: Before the timer contacts 26 and 27 are closed, the condenser 17 has been charged by the current source thru a circuit which includes terminal 10, resistance 16, condenser 17, primary *P* of coil 30, and ground return to the current source. Also the condenser 15 has been charged by the current source through the circuit which includes terminal 10, resistance 11, tap 13, resistance 14, condenser 15 and ground return. While the contacts are open, the tube 22 passes no current. At the instant ignition is required timer contacts 26 and 27 close thereby causing condenser 15 to discharge through a circuit which includes a condenser 15, contacts 27, 26, resistance 25, grid 24, cathode 28 and ground return to the condenser. The discharge of condenser 15 causes the tube 22 to become conducting whereupon the condenser 17 discharges through a circuit which includes cathode 28, plate 23, condenser 17, primary *P* of coil 30 and ground return to cathode 28. Coil 30 is so constructed that a current of high voltage and frequency is generated in the secondary *S* sufficient for ignition purposes even under conditions when the engine compression is high and spark plugs are fouled. It is only during the time condensers 15 and 17 are discharging through tube 22, that tube 22 is drawing current from the power supply through the resistance 16, although contacts 26 and 27 may remain closed thereafter. In this way the energy of the power supply is conserved.

A satisfactory high frequency ignition coil for use with the system will now be described with reference to Figs. 2 through 6. Primary *P* of coil 30 comprises two sections 31 each having four coils 32 in parallel. Secondary *S* has two sections 35 connected in series. There are two ignition coil units *C* (Fig. 4) each comprising four primary coils 32 and one of the secondary coil sections 35 wound upon the primary coil. An enlarged, sectional view of the unit *C* is shown in Fig. 6. To wind the coil unit, layers of insulating paper 40 are wound upon a removable core and four primary wires are grouped together and wound simultaneously in two layers with layers of insulating paper 41 between the layers of windings. This will locate the start leads 33 and the end leads 34 of the primary coils 32 on the same end of the coil unit *C* as shown in Fig. 4.

Upon the second layer of primary coils 32 a number of layers of insulating paper 42 are wound. The turns of a secondary coil 35 are wound over the insulating paper 42 beginning at the end of the assembly opposite to that from which the leads of the primary extend. The secondary coil 35 is wound in two layers so that the leads 36 and 37 of the secondary 35 extend from the same end of the coil unit C, that end being opposite the end from which the primary leads 33 and 34 extend. There is a layer of insulation 43 between the two layers of secondary turns and a wrapping of insulation 44 on the outside.

The two sections C surround parts of the core 45 which is formed by wrapping a thin steel strip upon a form to produce the shape shown in Fig. 5. A preferred material for the winding strip is hypersil steel .022 inch thick. After winding, the core is severed at the lines x and y to provide two parts which are butted together after the coil sections C are assembled with the core, and are retained by a band 46 which is wrapped around the core and the ends joined as indicated at 47.

The core and coil assembly is housed in a box 50 having a mounting bracket 51. The assembly is retained by angle brackets 52 secured to the box 50. As shown in Fig. 2, the coil sections C are positioned on the core 45 so that the primary leads are adjacent one side of the box 50 and the secondary leads are adjacent the opposite side of the box. Box 50 supports insulators 55a and 55b which support a terminal screw 54 retained by a nut 54a. To screw 54, the non-grounded lead 53 of the secondary coils 35 is connected. Wire 56 connects the two secondary coils. The other end lead 57 of the secondaries is grounded on the box 50. Terminal screw 54 is connected, as indicated in Fig. 1, with distributor 20.

The start leads 33 of one primary section 31 are attached to the finish leads 34 of the other primary section 31 and to flexible cables, and vice versa. The grounded flexible cable 58 is attached to the box 50. The non-grounded flexible cable 59 is connected with a terminal screw 60 passing through insulators 61a and 61b supported by the can 50 and held in assembled relation by a nut 60a. Terminal 60 is connected with condenser 17 as shown in Fig. 1.

All of the primary windings 32 operate cumulatively and the secondary windings also operate cumulatively. The parallel connections of the primary provide a path of relatively low resistance for the discharge of current from the condenser 17 and the secondary sections 45 being connected in series increase the output voltage over that obtained from one coil, the resultant increased voltage being available for ignition purposes.

Satisfactory electrical dimensions are as follows:

Resistance 11, 5 megohms, 2 watts

Resistance 12, .5 megohm, 1 watt

Resistance 14, .8 megohm, 1 watt

Resistance 16, 100,000 ohms, 50 watts

Resistance 25, 2,500 ohms

Resistance 29, 25,000 ohms

Condenser 15, .001 micro-farad

Condenser 17, .02 micro-farad

Each coil 32, 11 turns of #28 varnish-insulated wire

Each coil 35, 62 turns of #28 varnish-insulated wire

The thyratron tube 22 should contain hydrogen

or similar gas because its operation is not appreciably affected by temperature variations in the range ordinarily encountered in ignition service.

Referring to Fig. 1A, vertical line D—A represents the instant of closing of contacts 26, 27 and vertical line F—C the instant of contact opening. During time A—B, condenser 15 discharges to render tube 22 conducting and the condenser 17 discharges and ignition is effected. At B, tube 22 ceases to conduct because the condenser 17 has discharged and the voltage of condenser 15 is very low because the voltage available at 13 has been reduced by resistance 14 to a very low value at condenser 15. It will be seen that, while contacts 26, 27 are closed, there is a voltage divider circuit which includes resistances 14, 25, and 29 in series. Since resistance 14 has much greater resistance value than resistances 25 and 29 and condenser 15 is connected between resistances 14 and 25, the voltage which the condenser 15 receives while the contacts are closed is a very low value represented by line G—H. When contacts 26, 27 open, the charging of condenser 15 begins and its voltage rises as represented by curve H—I. The resistance value of resistances 14 should not be too high else the condenser 15 would not be charged in the time allowed and should not be too low else the voltage on condenser 15 would be so high that tube 22 would remain ionized during the period A—C when the contacts are closed and the tube 22 would be drawing current from the power supply and energy would be wasted. One aim is to minimize consumption of energy which is represented by the shaded area in Fig. 1A bounded by lines A—B and D—E which represent the time during which the tube 24 is ionized and lines D—A and E—B which represent current passed by the tube.

The function of resistance 14 is to control the rate of charging of condenser 15. It holds the voltage applied to condenser 15 to a very low value until the contacts open and permits the voltage of the condenser to increase, in the time allowed, to a value sufficient to effect ionization of tube 22 when the contacts close.

The function of resistance 25 is to limit the current passing to the grid of tube 24 during the ionization period.

The function of resistance 29 is to prevent the grid 24 from floating thereby preventing the tube 22 from becoming conducting except at the proper time.

The function of resistance 16 is to limit the charging current of condenser 17. At the instant represented by line E—B when the tube 22 ceases to conduct, the charging of condenser 17 begins. As the condenser 17 receives charge, its charging current is represented by line E—J. If resistance 16 were omitted and terminal 10 were directly connected with the condenser 17 and the plate 23 of tube 22, the charging of condenser 17 would begin at a very high rate under high potential and the tube 22 would be destroyed. The resistance 16 holds back the charging peak current by effecting a substantial voltage reduction so that charging begins at a moderate current value represented by line E—B.

While the embodiment of the present invention as herein disclosed, constitutes a preferred form, it is to be understood that other forms might be adopted, all coming within the scope of the claims which follow.

What is claimed is as follows:

1. An ignition system comprising a direct current source, a high frequency ignition coil having

primary and secondary windings, a distributor connected with the secondary coils, a main condenser, a main condenser charging circuit including the source, the main condenser and a resistance for limiting the charging circuit to a suitable maximum, a main condenser discharging circuit including the main condenser, the primary windings of the ignition coil and a thyatron, an auxiliary condenser, an auxiliary condenser charging circuit including the source, a resistance and the auxiliary condenser, and an auxiliary condenser discharging circuit including the auxiliary condenser, the contacts of an ignition timer and the grid of the thyatron, the closing of the timer contacts causing the auxiliary condenser to discharge to the thyatron grid and render the thyatron conducting whereby the main condenser discharges and ignition is provided, the value of the second mentioned resistance being such that, after the auxiliary condenser has discharged, the thyatron ceases to conduct because the voltage at the auxiliary condenser is held by the said resistance to a low value while the timer contacts are closed.

2. An ignition system comprising a direct current source, a high frequency ignition coil having primary and secondary windings, a distributor connected with the secondary coils, a main condenser, a main condenser charging circuit including the source, the main condenser and a resistance for limiting the charging current to a suitable maximum, a main condenser discharging circuit including the main condenser, the primary windings of the ignition coil and a thyatron, an auxiliary condenser, a voltage divider resistance connected with the current source, an auxiliary condenser charging circuit including the auxiliary condenser and a third resistance connected to a

tap of the voltage divider, an ignition timer having contacts one of which is connected to a terminal of the auxiliary condenser, a fourth resistance connected to the other timer contact and the grid of the thyatron for controlling the discharge of the auxiliary condenser to the grid when the timer contacts close to render the thyatron conducting whereby the main condenser discharges and ignition is provided, and a fifth resistance connected to the grid and cathode of the thyatron to prevent floating of the grid, said third, fourth and fifth resistances providing, while the timer contacts are closed, a second voltage divider circuit connected to the tap of the first voltage divider, the auxiliary condenser being connected between the third and fourth resistances, the resistance value of the third resistance being substantially greater than the resistance values of the fourth and fifth resistances whereby the voltage at the auxiliary condenser is held to such low value after the auxiliary condenser has discharged and before the contacts open that the thyatron ceases to conduct after the auxiliary condenser has discharged.
